UNITED STATES PATENT OFFICE.

LOUIS E. EICKELBERG, OF WATERLOO, IOWA.

BUCKSAW-FRAME.

SPECIFICATION forming part of Letters Patent No. 642,593, dated February 6, 1900.

Application filed May 12, 1899. Serial No. 716,531. (No model.)

To all whom it may concern:

Be it known that I, LOUIS E. EICKELBERG, a citizen of the United States of America, and a resident of Waterloo, Black Hawk county, 5 Iowa, have invented certain new and useful Improvements in Bucksaw-Frames, of which the following is a specification.

This invention relates to woodworking-tools, and more especially to that class thereof 10 known as "saw-handles;" and the object of the same is to produce an improved bucksaw frame or handle and means for tightening it.

To this end the invention consists in a construction whereby the blade is strained or 15 stretched by the simultaneous action of two forces, one of which is capable of adjustment, all as hereinafter more fully described and claimed, and as shown in the accompanying drawings, wherein—

20 Figure 1 is a side elevation of my improved frame with its adjustment more clearly shown enlarged in Fig. 2.

The frame comprises a handle C, preferably of wood, and the beam A, having one 25 end n forked and provided with a series of holes for adjustable connection to the handle, and its other end turned down, as shown, and bolted to one extremity of the plate B, whereof the other extremity is connected with the

30 handle, and the center of the beam, which latter is preferably of tubular metal, is depressed out of a true straight line, as at m. With these elements is combined a series of rods connecting the upper end of the handle 35 with the downward bend of the beam, and the length of this rod may be adjusted as described below. The rod holds the beam practically always at one angle to the handle except when adjustment occurs, and the tension on this rod turns said handle over the 40 pivotal point n, so as to draw the blade B tight. The depression m of the beam, which throws the latter out of a true straight line, also brings into play the resilience which this

45 metal beam will have, a force which is enhanced by the rod connecting the beam with the handle. Thus whether the adjustment takes place in the length of the rod or in the point of connection between the beam and 50 handle, or even if there is no adjustment, the normal tendency of the depressed portion m

to straighten out will tighten the blade to a considerable extent. The rod is made in two members d e and f g, which are preferably flattened where they lap each other, and the 55 inner edge of one member notched, as shown, and using a tie-bar h k, having holes h' k' near its ends, which embrace the lapping ends of the members. One of the latter has a head at its inner end, as seen in Fig. 2, and when 60 the tie-bar is in place and tension is applied it cant on the member d e, so that the hole h' presses against the head, while the hole k' engages the back of the other rod f g and enters one of the notches in its front edge. The 65 outer ends of the rods, as at d and g, are engaged, respectively, with the beam A, where it bends downward, and with the upper end of the handle C. After inserting the blade B and adjusting at n, as necessary, the rods 70 or members are drawn toward each other forcibly and connected by any form of adjustment that is employed.

All parts are preferably of metal, excepting the handle, which is preferably of wood. The 75 latter is sprung to a certain extent around its pivotal point n, and hence the yielding force of the wooden handle assists the specific construction of the beam A in straining the blade B tight between its extremities. 80

What is claimed as new is—

1. A bucksaw-frame comprising a substantially upright handle, a beam connected at one end to about the center of the handle and having its other end turned down for attachment to the blade, a rod in two members whose outer ends are respectively connected with the upper end of the handle and with the beam where it is turned down, and a tie-bar having holes receiving the inner lapping 85 ends of said rods and adapted to bind thereon when the tie-bar is canted, as and for the purpose set forth.

2. A bucksaw-frame comprising a substantially upright handle, a beam connected at 95 one end to about the center of the handle and having its other end turned down for attachment to the blade, a rod in two members whose outer ends are respectively connected with the upper end of the handle and with the beam where it is turned down and whose inner ends are respectively provided with a

head on one member and with notches in the inner edge of the other, and a tie-bar having holes near its ends respectively engaging said headed member and said notched member and 5 adapted to enter one of the notches when the bar is canted, as and for the purpose set forth.

Signed by me at Waterloo, Iowa, this 9th day of May, 1899.

LOUIS E. EICKELBERG.
